US0D1106167S

(12) **United States Design Patent** (10) **Patent No.:** **US D1,106,167 S**
(45) **Date of Patent:** **** Dec. 16, 2025**

(54) **WEARABLE ELECTRONIC DEVICE**

(71) Applicant: **Samsung Electronics Co., Ltd.**, Suwon-si (KR)

(72) Inventors: **Jinwook Kim**, Suwon-si (KR); **Junho Jin**, Suwon-si (KR)

(73) Assignee: **SAMSUNG ELECTRONICS CO., LTD.**, Gyeonggi-Do (KR)

(**) Term: **15 Years**

(21) Appl. No.: **29/905,451**

(22) Filed: **Oct. 20, 2023**

(30) **Foreign Application Priority Data**

Jul. 14, 2023 (KR) 30-2023-0027228

(57) **CLAIM**

The ornamental design for a wearable electronic device, as shown and described.

DESCRIPTION

FIG. 1 is a front perspective view of a wearable electronic device, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is a rear perspective view thereof.

The broken lines depicting portions of the wearable electronic device form no part of the claimed design.

1 Claim, 8 Drawing Sheets
